United States Patent Office

Des. 221,439

Patented Aug. 17, 1971

221,439

AUTOMOBILE TAPE PLAYER OR SIMILAR ARTICLE

Robert E. Mowris, Janesville, Wis., assignor to Gibbs
Special Products Corporation, Janesville, Wis.

Filed Feb. 16, 1970, Ser. No. 21,455

Term of patent 14 years

Int. Cl. D14—01, 03

U.S. Cl. D26—14

Fig. 1.

Fig. 2.

Fig. 3.

FIG. 1 is a front elevation of an automobile tape player or similar article showing my new design;

FIG. 2 is a right end view showing the front portion to the left; and

FIG. 3 is a top plan view of the front portion.

The left side is substantially the same as the right disclosed in FIG. 2 and the undisclosed rear portion is plane and unornamented.

I claim:

The ornamental design for an automobile tape player or similar article, as shown and described.
